UNITED STATES PATENT OFFICE.

JAMES D. CUMMINGS, OF HOUSTON, TEXAS.

SCRAPER ATTACHMENT FOR TRACTORS.

Application filed April 22, 1927. Serial No. 185,710.

My invention relates to tractor operated scrapers for use in filling earth into ditches or trenches.

The invention constitutes an improvement upon the invention disclosed in the Patent No. 1,522,378, granted on January 6th, 1925, to me jointly with J. E. McLeod. The device is for use primarily in filling in ditches in which pipe lines are laid, but may 10 be adapted for a wide variety of uses.

It is an object of the invention to provide a scraper which may be attached to the forward end of a tractor and to the housing of the crank case thereof, in such manner as to 15 allow flexibility in the adjustment of the attachment upon the tractor in use.

An object is to provide a universal engagement between the scraper and the push bars so that the angle of adjustment of the 20 scraper may be changed in various planes without difficulty.

The improvements in the present invention over the prior device, referred to above, lie largely in details of construction, where- 25 by the scraper may be more firmly sup- ported and more readily adjusted.

Referring to the drawings herewith, forming a part of this specification, for a more particular understanding of the invention, 30 Fig. 1 is a broken side elevation of a tractor showing my invention mounted thereon, certain parts being broken away for clear- ness. Fig. 2 is a broken rear view of the 35 scraper showing the means of attachment thereto of the push bars. Fig. 3 is a top plan view of the attachment removed, cer- tain parts being broken away and removed.

The scraper disclosed is designed to be employed to cut into a bank of earth and 40 push the earth before it. In filling ditches the earth is pushed toward the ditch and dumped therein. The scraper 1 is a plate of steel of suitable length, curved in vertical section to present a concave face forwardly 45 to engage the earth. The lower edge of the plate is sharpened at 2 to better cut into the earth.

The plate or mould board 1 is supported at the forward ends of push bars 3, 3, which 50 are themselves mounted upon the tractor 4. The push bars are extended forwardly from a point directly below the crank case 5 of the tractor. The rear ends of the bars 3 are secured within a casting 6 which has

diverging sockets in which the bar ends are 55 secured.

The casting 6 has a central opening 7 therein to receive an upright pin 8. Said pin is supported within a bracket 9 bolted to the flange 10 of the crank case. This mount- 60 ing furnishes an extremely rigid and firm attachment at a point spaced forwardly from the drive wheels 11 of the tractor.

The arms 3 diverge forwardly and are of tubular formation. The forward ends of 65 said arms telescope over rods 12 which fit slidably therein. Each of said rods has at its forward end a ball 13 formed integral with the rod. A radial flange 14 on the rod adjacent the ball limits the movement of the 70 rod into the push bar arm.

The push bars 3 are supported adjacent their forward ends by yokes 15, as shown in my prior Patent No. 1,522,378, previously mentioned. The said yoke has two collars 75 16 formed to receive the push bar. Above the push bar, the yoke is extended upwardly and has a slot 17 therein, longitudinally of the bar, to receive a crank arm 18, upon a lever 19, pivoted upon a rock shaft 20. The 80 said shaft is mounted pivotally within a bearing 21 bolted to the forward side of the front axle 22 of the tractor.

The lever 19 is formed with a connecting arm 23 which joins with an arm 24 secured 85 to shaft 20, the three arms 19, 23 and 24 being preferably formed in an integral tri- angular frame. The upper ends of arms 23 and 24 are pivotally connected to a link bar 25 extending rearwardly for control by 90 the operator in any preferred manner, the operating connection being omitted. The crank arm 18 is slidable in the slot 17 of the yoke when the lever is operated.

There are supporting yokes 15 for each 95 push bar and a transverse pin 27 through the forward sleeve 16, the bar 3 and the rod 12 serves to hold the rod in position in the bar. A plurality of transverse openings 28 are formed therein to receive said pin 27 100 so that the length of each bar may be thus varied, as best seen in Fig. 3. The adjustable length of the push rods makes the device adaptable to push the earth to the right, left or forward in any degree desired.

The scraper plate 1 is formed on its rear- 105 ward side with a longitudinal slideway formed of two spaced angle irons 29, hav-

ing overhanging flanges 30 to slidably engage a bearing block 31. The forward face of said block is curved to fit against the scraper and has a rearward socket 32 therein to receive the ball 13 upon the push bar. There are bearing blocks 31 for each bar both slidable in the slideway between the irons 29. The lower of the slideway guides has spaced notches 33 therein and each block 31 has a pivoted latch dog 34 thereon to engage with a selected one of these notches to hold the block from sliding during operation of the scraper.

At the upper edge of the scraper is a rod 35 supported at each end in brackets 36 upon the plate. Upon this rod are slidably mounted two sleeves 37 which have ears 38 thereon pivotally connected to the forward ends of arms 40. Said arms 40 extend rearwardly and are connected to the yoke 15 at any one of a plurality of openings 41, thus furnishing a support for the upper side of the scraper plate. The support arms are made in two telescoping sections 40 and 40' similar to the push rods 3. A pin 42 serves to retain the parts in the desired position as do the pins 27 in the push rods. Thus when the push rods are extended as shown in Fig. 3 the support arms also are extended an appropriate amount.

In operation, the scraper will most frequently be extended transversely at approximately a right angle to the line of travel, as shown in full lines in Fig. 3. The bearing blocks 31 will be locked in the proper position to support the scraper plate at that angle. This will be accomplished by dropping the latching dogs 34 into any selected one of the notches 33, in the manner shown in Fig. 2. The connecting arms 40 may be adjusted in any one of the openings 41 so as to tilt the scraper plate at the desired angle and ordinarily the position will be approximately erect, as shown in Fig. 1.

In filling earth into ditches and trenches, as is necessary in the laying of pipe lines and the like, the lever 25 will be withdrawn toward the operator so as to raise the scraper off the ground and the tractor will then be backed up so as to bring the scraper against the wall of earth which is to be moved into the ditch. The operator will then drop the scraper to the proper position to engage the bank of earth and the tractor will be advanced so as to push the earth into the ditch or excavation which is to be filled. This operation will be repeated until the earth has been entirely filled into the ditch.

When the device is to be used in scraping roads or smoothing off the ground after the earth has been filled in, it is frequently desirable to incline the scraper relative to the line of travel, as shown in dotted lines in Fig. 3. This will give the scraper blade a plow action which tends to throw the earth

more to one side of the path of the tractor. This inclining or tilting of the scraper may be done by removing the pin 27 on the bar which is to be lengthened and advancing the rod 12 from within the bar so as to engage the pin within one of the other openings 28. When thus adjusted, the plate will be as firmly supported as before and the universal connection between the rod 12 and the bearing block upon the plate will allow the same firm contact between the push bar and the plate. In thus inclining the plate, it may be necessary to slide one or both of the bearing blocks 31 within the slideway 29 so as to accommodate the change in the position of the blade. Also the upper supporting arms 40 will have their connection 37 with the rod 35 adjusted slidably along the rod to allow adjusted arrangement of the blade.

It will be obvious that the scraping blade 85 may be raised and lowered readily and the position of the scraper plate relative to the tractor may be varied both in a vertical and horizontal plane. This provides an extremely flexible type of scraper which is also 90 simple and strong in its construction and not liable to get out of order.

The advantages of the structure will be obvious to those skilled in the art.

What I claim as new and desire to protect 95 by Letters Patent is:

1. A scraper attachment for tractors including a scraper plate, push bars therefor, a supporting bracket for said bars secured to the lower side of said tractor, rods adjustable longitudinally in the forward ends of said bars, slideways on the rearward side of said plate, bearing blocks slidable therein, and universal connections between said rods and said blocks. 100

2. A scraper attachment for tractors including a scraper plate, push bars therefor, a supporting bracket for said bars secured to the lower side of said tractor, rods adjustable longitudinally in the forward ends 110 of said bars, slideways on the rearward side of said plate, bearing blocks slidable therein, universal connections between said rods and said blocks, and supporting arms slidably connected with the upper side of said scraper plate for the purpose described. 115

3. In a tractor having a crank case, a front axle, and drive wheels, the combination of an attachment including a scraper plate, a bracket on said crank case, a push bar casting secured to said bracket, push bars supported by said casting, the forward ends of said bars being extensible, and a universal connection between said bars and said scraper plate. 120

4. In a tractor having a crank case, a front axle, and drive wheels, the combination of an attachment including a scraper plate, a bracket on said crank case, a push bar casting secured to said bracket, push 130

bars supported by said casting, the forward ends of said bars being extensible, a universal connection between said bars and said scraper plate, and means to raise and lower 5 said bars and said scraper plate.

5. In a tractor having a crank case, a front axle, and drive wheels, the combination of an attachment including a scraper plate, a bracket on said crank case, a push 10 bar casting secured to said bracket, push bars supported by said casting, the forward ends of said bars being extensible, bearing blocks adjustable longitudinally of said plate and a universal connection between 15 said bars and said bearing blocks.

6. In a tractor including front and rear wheels, an attachment including a scraper plate, push bars supported on the under side 20 of said tractor in front of said rear wheels, bearing blocks connected with said bars and adjustable on said scraper plate, said push bars being extensible to allow adjustment of 25 said plate, means to raise and lower said bars and plate, and adjustable means to support the upper edge of said plate.

7. In a tractor including front and rear wheels, an attachment including a scraper plate, push bars supported on the under side 30 of said tractor in front of said rear wheels, bearing blocks connected with said bars and adjustable on said scraper plate, said blocks having sockets therein, balls on said bars fitting within said sockets, said push bars being extensible to allow adjustment of said

plate, means to raise and lower said bars and 35 plate, and adjustable means to support the upper edge of said plate.

8. A tractor attachment including push bars adapted to be supported at their rear ends beneath said tractor, a scraper plate, 40 longitudinal slideways on said plate, bearing blocks adjustable in said slideways, sockets in said blocks, rods adjustable in said bars, balls on said rods engaging in said sockets, means to raise and lower said bars, and 45 means to support one edge of said plate.

9. A tractor attachment including a scraper plate, a plurality of push bars connected with said tractor, universal connections between said bars and said plate, and 50 supports for the upper edge of said plate, said bars and supports being adjustable longitudinally along said plate and also in the direction of travel.

10. A tractor attachment including a 55 scraper plate, a pair of diverging push bars connected with said tractor, universal connections between said bars and said plate, a rod secured at both ends along the upper side of said plate, and supports for the upper edge of said plate secured slidably on 60 said rod, said bars and supports being adjustable longitudinally along said plate for the purpose set forth.

In testimony whereof I hereunto affix my 65 signature this 16th day of April, A. D. 1927.

JAMES D. CUMMINGS.
